ARTIFICIAL LEG

Ferdinand Buchstein, Minneapolis, Minn.

Application April 4, 1934, Serial No. 718,935

1 Claim. (Cl. 3—2)

My present invention relates to artificial body members and more particularly to artificial legs. Heretofore, artificial legs have been carried from the shoulder or shoulders of the wearer by suspenders or other devices which are highly objectionable for the reason that they chaff the wearer, are uncomfortable and unsightly, particularly when the wearer has on thin clothes or goes without a coat.

One of the objects of this invention is the provision of simple and highly efficient means, including a pelvic girdle, for carrying an artificial leg suspended from one of the hip bones of the wearer.

A further object of the invention is the provision of a simple and highly efficient motion control device for the lower leg section and which device is connected to the pelvic girdle.

A further object of the invention is the provision of a novel knee joint.

Other objects and advantages of the invention will hereinafter be made fully apparent in the specification and pointed out in the claim.

To the above end, generally stated, the invention consists of the novel devices and combinations of devices hereinafter described and defined in the claim.

In the accompanying drawings, which illustrate the invention, like characters indicate like parts throughout the several views.

Referring to the drawings:

Fig. 1 is a right side elevation of an artificial leg applied to a human body diagrammatically and fragmentarily illustrated by means of broken lines;

Fig. 2 is a front elevation of the parts shown in Fig. 1, with some parts broken away;

Fig. 3 is a view in vertical section taken on the line 3—3 of Fig. 1, on an enlarged scale;

Fig. 4 is a fragmentary detail view in section taken on the line 4—4 of Fig. 3;

Fig. 5 is a view principally in section taken on the line 5—5 of Fig. 3; and

Fig. 6 is a view corresponding to Fig. 1 but showing the body and artificial leg in a sitting posture with a portion of the lower leg section broken away.

The artificial leg illustrated is for an amputation above the knee and for the purpose of showing the same in working position, there is fragmentarily illustrated in the drawings, a portion of a human body X.

Of the parts of the artificial leg illustrated, it is important to note the foot section 1, the lower leg section 8, and the upper leg section 9. Both

leg sections 8 and 9 are of a hollow structure. The joint between the foot section and the lower leg section 8 is indicated as an entirety by the numeral 10 and may be of any well-known construction.

The knee joint, which is of novel construction, includes a pair of axially aligned hubs 11 formed with the upper end portions of a pair of metallic straps 12 which extend into the lower leg section 8 and are rigidly secured, one to each side thereof.

Extending axially through the hubs 11 is a bolt 13 having on its inner end a large screw-head 14 which impinges against the outer face of the inner hub 11. The bolt 13 has screw-threaded engagement with the inner hub 11, as indicated at 15. A screw 16, having a head 17 similar to the head 15, extends into the tapped outer end portion of the bolt 13 and has screw-threaded engagement therewith. The bolt 13 is held from turning about its axis in the inner hub 11 by the head of a screw 18 which extends into a notch in the periphery of the screw-head 14. This screw 18 has threaded engagement with the inner hub 11. A screw 19, similar to the screw 18, has threaded engagement with the outer hub 11 and its head extends into a peripheral notch in the screw-head 17 and holds the screw 16 from turning relative to said hub and the bolt 13.

The improved knee joint further includes a pair of axially aligned ball bearings which include outer ball races 20, rigidly secured to the upper leg section 9 in apertures in the sides thereof, inner ball races 21, through which the bolt 13 extends axially, and series of balls 22 interposed between the races 20 and 21. By reference to Fig. 3 it will be noted that the inner ball races 21 impinge against the inner faces of the hubs 11 and the outer ball races 20 are out of contact with said hubs.

A long spacing sleeve 23 is mounted on the bolt 13 between the ball bearings and a crank or lever 24 is carried by said sleeve. The lever 24 comprises a pair of laterally spaced and radially projecting prongs 25, integral at their inner end portions with said sleeve, and a roller-equipped pin 26 mounted on and between the prongs 25, at their outer end portions.

It is important to note that the spacing sleeve 23 at its ends engages the inner ends of the inner ball races 21 and positively holds the same, as well as the hubs 11, against axial movement toward each other. It will thus be seen that the bolt 13 holds the inner ball races 21 clamped between the inner ends of the inner ball races 21 and the outer ends of the outer ball races 20.

tween the hubs 11 and the sleeve 23 and positively holds the same from turning on the bolt 13. With the inner ball races 21 thus held, the outer ball races 20, and hence the upper leg section 9, are free to move about the axis of the knee joint. A plurality of screws 27 connect the lever 24 to the spacing sleeve 23. The lever 24 forms a part of a motion control device for the lower leg section 8, as will hereinafter appear.

10 Referring now in detail to the means for carrying the artificial leg from the body X, and which means comprises a buckle-equipped pelvic girdle 28 having a hanger. This hanger includes a metal bow 29 and a stiff curved metal strap 30 to which the ends of said bow are rigidly secured. The strap 30 is rigidly secured by rivets or otherwise to the girdle 28 and extends around the right side of the body X and considerably beyond the ends of the bow 29. The girdle 28 and the hanger 20 29-30 are connected to the upper leg section 9 by a quadruple joint. This joint is in the form of a pair of metal links 31 that are crossed in X-shaped arrangement. These links 31 are pivoted, at their upper ends to the strap 30, midway between the ends of the bow 29, and their lower ends are pivoted to a bracket 32 rigidly secured to the upper leg section 9, at the outer side and top thereof. The bow 29 is padded and covered with leather or other suitable material.

30 The bow 29 is constructed and arranged to extend over the ilium or crest of the hip bone above the artificial leg. By reference to Fig. 2 it will be noted that the upper portion of the bow 29 is curved outwardly and upwardly to more clearly 35 follow the contour of the body X.

Obviously, the girdle 28 holds the bow 29 drawn tight against the body X so that the upper portion thereof extends over the ilium and supports the artificial leg thereto.

40 The motion control device for the lower leg section 8, heretofore referred to, further includes a strap 33, the intermediate portion of which is arranged to run over the roller-equipped pin 26. The end portions of the strap 33 extend outwardly and upwardly through front and rear apertures in the upper leg section 9 above the lever 24 and the ends of said strap are adjustably attached by buckles 34 to the lower ends of a pair of elastic

straps 35. Said straps 35 at their upper ends are anchored to the metal strap 30 at the ends of the bow 29. In a broad sense, the elastic straps 35 form sections of the strap 33. The end portions of the strap 33, where the same pass through the apertures in the upper leg section 9, run over flanged rollers 36 journaled on fixed bearing 37 rigidly secured to the upper leg section 9 on the inside thereof, see Fig. 4. It is important to note that the lever 24, see Fig. 5, extends upwardly and forwardly from the axis of the knee joint so that the elastic straps 35 are placed under tension by said lever when the artificial leg is bent at the knee joint.

Within the upper leg section 9 is a stop block 15 38 rigidly secured to said leg section, at the back thereof, and arranged to be engaged by the lever 24 to limit the forward swinging movement of the lower leg section 8 and align the same with the upper leg section 9. The quadruple joint 31 gives the artificial leg a free and natural swinging movement from the girdle 28 and the hanger 29-30 to which it is connected.

It will be understood that the invention described is capable of various modifications within the scope of the invention herein disclosed and claimed.

What I claim is:

The combination with an artificial leg of an upper leg section and a lower leg section, of a girdle adapted to be applied around a body below the crest of the hip bones and having a hanger comprising a bow extending upwardly above said girdle and a metal reinforcing strap connecting the ends of the bow, said bow being adapted to fit over the crest of one of the hip bones, a joint connecting the upper leg section to the girdle, said joint comprising a pair of crossed metal straps having one of their ends pivoted to the metal reinforcing straps between the ends of the bow, the other ends of the crossed metal straps being attached to the upper leg section, and a motion control device for the lower leg section including a flexible strap, the ends of which are attached to the reinforcing strap in the vicinity of the ends of the bow.

FERDINAND BUCHSTEIN.
